UNITED STATES PATENT OFFICE.

WILLIAM J. ROST, OF CANTON, OHIO, ASSIGNEE TO THE GIBBS MANUFACTURING COMPANY, OF CANTON, OHIO, A CORPORATION OF OHIO.

FIGURE WHEELED TOY.

Application filed May 8, 1928. Serial No. 276,029.

My invention relates to toy figures, and more particularly to toy figures of animals and the like, arranged to simulate natural movements when propelled across the surface of a floor, table top, or the like.

Toy figures of many descriptions have been proposed in which the legs of the figures are arranged to move; but the natural movements of the various species and varieties of animals when walking and running, include different kinds of movements of body parts, simultaneously with the leg movements.

The running movement of a rabbit, for example, is characterized by an up and down movement of the head and forelegs with respect to the torso, and by movement of the hind legs forward and to the rear with respect to the torso, and by relatively slight oscillations of the torso with respect to the horizontal, all the movements occurring simultaneously with each other.

Accordingly the objects of the present improvements include the provision of a mechanical toy figure of an animal, arranged to be propelled by movement across a flat surface, so that the head and front legs, the torso, and the hind legs will all have movements relative to each other and to the horizontal, and will simulate the running movements of a live animal.

These and ancillary objects are attained in the present improvements by a novel construction and arrangement which will be hereinafter set forth in detail and claimed.

Although the present improvements may be utilized to provide animal figures of any desired species or variety; for example, a preferred embodiment of the invention in which the figure simulated is that of a rabbit, is illustrated in the accompanying drawing forming part hereof, in which

Figure 1 is a fragmentary top plan view of a mechanical toy rabbit figure embodying the present improvements;

Fig. 2, an elevation view of one side thereof, with portions broken away, the movable parts thereof being located in one of the positions assumed thereby when the toy is in use; and

Fig. 3, a similar view, with the movable parts thereof in another of the positions assumed thereby when the toy is in use.

Similar numerals refer to similar parts throughout the several views.

The improved toy rabbit figure indicated generally at 10, includes a torso member 11 which may be profile cut from laterally spaced sheet metal plates 12 and 12', connected at their upper edges by a laterally and longitudinally extending strip 13, thus forming a U shaped torso member which may be formed and bent from an integral piece of sheet metal.

A head member 14 which may be profile cut from a wooden board of suitable thickness, is interposed between and preferably connected with the front ends of the torso member plates, as by means of a tubular rivet 15, and forelegs 16 and 16' may be secured at a suitable location at each side of the head member, the forelegs preferably each have the same profile as the other, and may be cut or blanked from sheet metal, and secured to the head, as by means of a tubular rivet 17.

Hind leg and tail member plates 18 and 18', preferably each having the same profile as the other, and which may be cut or blanked from sheet metal, are connected at their upper ends by means of a laterally and longitudinally extending strip 19, thus forming a U shaped pair of legs and a tail which may be formed and bent from an integral piece of sheet metal.

The hind leg and tail member plates 18 and 18' are interposed between the torso member plates 12 and 12', and are pivotally connected therewith at a suitable location as by means of a tubular rivet 20.

Intermediate the front rivet 15 and the rear rivet 20, a torso member supporting pivot rivet 21 is provided, and the ends thereof are journalled in bearing loops 22 and 22' formed respectively at the outer extremities of a pair of bent wires 23 and 23', constituting a supporting frame 24 for the toy, the rear ends of the wires being twisted together to form a rear angled handle extremity 25.

Intermediate the handle extremity 25 and the upper bearings 22 and 22', the wires are angled and bent to form a pair of laterally spaced bearing loops 26 and 26', in which are journalled portions of a crank axle 27, which carries at its outer ends laterally spaced wheels 28 and 28', and has formed in its central portion a crank 29.

A forward connecting rod 30 is pivotally connected at its lower end with the crank 29,

and is pivotally connected at its upper end as at 35 with the head 14, preferably at the rear of the pivot rivet 15.

A rear connecting rod 31 is pivotally connected at its lower end with the crank 29, and is pivotally connected at its upper end as at 32, with the hind leg and tail member plates 18 and 18', preferably below and at the rear of the pivot rivet 20.

10 Thus the head member 14, and the integral hind legs are each provided with an independent connecting rod connection with the crank 29, and the torso member is itself supported for oscillation on the frame 24 by the 15 pivot rivet 21; whereby the head member and forelegs, the hind leg member, and the torso member, are each oscillated simultaneously with each other, when the wheels 28 and 28' rest upon the surface 33 of a floor or the like, 20 and the toy is pushed across the floor as by means of a handle 34 secured upon the handle extremity 25.

Several parts of the toy rabbit figure are accordingly given movements very similar to 25 the movements of a live rabbit in running.

An outwardly projecting lug 36 is preferably provided at each side of the wires 23 and 23' below the pivot rivet 21, to limit the oscillation of the torso member 11.

30 I claim:

1. A figure toy including a torso member, a head member, and a hind leg member, means pivotally mounting the head member on the torso member at one end thereof, means pivotally mounting the hind leg member on the torso member at the other end thereof, a frame, means pivotally mounting the torso member on the frame, an axle journaled in the frame, a crank on the axle, a connecting 35 rod pivotally connected at one end with the crank and at the other end with the head member, and another connecting rod pivotally connected at one end with the crank and at the other end with the hind leg member.

45 2. A figure toy including a frame, a torso member pivoted intermediate its ends to the frame, a head member, and a hind leg member, means pivotally mounting the head member on the torso member at one end thereof, means pivotally mounting the hind leg member on the torso member at the other end thereof, an axle journaled in the frame substantially directly below the torso member 50 pivotal point, a crank on the axle, a connect-

ing rod pivotally connected at one end with the crank and at the other end with the head member, and another connecting rod pivotally connected at one end with the crank and at the other end with the hind leg member.

55 3. A figure toy including a torso member, a head member, and a hind leg member, means pivotally mounting the head member on the torso member at one end thereof, means pivotally mounting the hind leg member on the torso member at the other end thereof, a frame, means pivotally mounting the torso member on the frame, an axle journaled in the frame, a crank on the axle, a connecting rod pivotally connected at one end with the crank and at the other end with the head member, another connecting rod pivotally connected at one end with the crank and at the other end with the hind leg member, and means actuated by moving contact with a surface for rotating the axle thereby operating the connecting rods to oscillate the head and hind leg members about their pivotal mountings, and the oscillation of the head and hind leg members imparting an oscillating movement to the torso member about its 65 pivotal mounting.

70 4. A figure toy including a torso member, a head member, and a hind leg member, means pivotally mounting the head member on the torso member at one end thereof, means pivotally mounting the hind leg member on the torso member at the other end thereof, a frame, means pivotally mounting the torso member on the frame, an axle journaled in the frame, a crank on the axle, a connecting 75 rod pivotally connected at one end with the crank and at the other end with the head member, another connecting rod pivotally connected at one end with the crank and at the other end with the hind leg member, means actuated by moving contact with a surface for 80 rotating the axle thereby operating the connecting rods to oscillate the head and hind leg members about their pivotal mountings, and the oscillation of the head and hind leg members imparting an oscillating movement to the torso member about its 85 pivotal mounting.

90 In testimony that I claim the above, I have 95 hereunto subscribed my name.

WILLIAM J. ROST.
